UNITED STATES PATENT OFFICE

2,550,040

SELECTIVELY EVACUATED TEMPERATURE
REGULATED CONTAINER

Mottel Clar, Culver City, Calif.

Application August 8, 1946, Serial No. 689,290

4 Claims. (Cl. 257—3)

1

This invention relates to storage and shipping containers of novel construction and operation, to an improved method of preserving and transporting perishable goods such as food products and to various integral features of construction which contribute to the particular effectiveness of my containers.

It is an object of the invention to provide a food container having means for regulating the temperature of the products stored therein such as by circulation of heated and cooled air, and further having a vacuum compartment which may either be the storage chamber or may surround the storage chamber to serve as an insulating space therefor. In one embodiment, my container is provided with means for selectively evacuating either the storage chamber or the surrounding insulating space, and also with means for circulating air through whichever of these spaces is not evacuated, so that the environment of the stored articles may be adapted to the particular product as well as adjusted in relation to the external conditions or temperature of the region in which they are stored or through which they are being transported.

Another purpose is to provide a container of the character described which is constructed of hollow demountable panels which may be assembled, for example, as the lining of a railroad car, aircraft, automotive truck, cargo vessel or, again, may be assembled and dismounted in a warehouse or other storage space as needed from time to time.

A further object is the provision of a reusable container of the character described which has no protruding attachments or parts so that a number of such units may be quickly and compactly stacked or lodged in a storage or shipping space, and in this connection there is provided a novel coupling assembly or high speed union for quickly connecting and disconnecting the container to suitable external means for evacuating and/or circulating heated or cooled air through the several closed spaces as required.

An additional purpose is to provide a container of the character described wherein the several principal walls are effectively insulated from each other as well as from conduits necessarily penetrating the walls.

Still another object is the provision of a container of the character described which is provided with a hollow door or closure which may be evacuated simultaneously with an insulating space of the container; another feature is a floating hinge construction which permits a more

2

exact and airtight alignment of the door in the door-way; still another feature is the provision of a door locking device particularly adapted for a storage chamber of the present type.

Other objects and advantages of the invention will be apparent from the following description and claims, the novelty consisting in the features of construction, combination of parts, the unique relations of the members and the relative proportioning, disposition, and operation thereof, all as more completely outlined herein and particularly pointed out in the appended claims.

In the drawings, which form part of the present specification:

15 Figure 1 is a longitudinal vertical sectional view through my storage chamber;

Figure 2 is a perspective view of my storage chamber as seen from above;

Figure 3 is a slightly enlarged fragmentary lateral sectional view taken through the container along the line 3—3 of Figure 1;

Figure 4 is an elevational view of the back of the container showing the door leading to the internal control panel where external air and vacuum lines are connected to service the unit;

Figure 5 is a fragmentary sectional view taken along the line 5—5 in Figure 4, showing the door handle in side elevation;

Figure 6 is a fragmentary sectional view taken through the inner chamber along the line 6—6 of Figure 4 and showing the vacuum line horizontally disposed along the inner chamber wall;

Figure 7 is a front elevational view of a modified form of my storage chamber with the door open;

Figure 8 is an elevational view of one form of container door;

Figure 9 is a sectional view through the door-locking mechanism taken along the line 9—9 of Figure 8;

Figure 10 is an elevational view of a housing assembly employed to anchor and insulate conduits which pass through the walls of my containers;

Figure 11 is an axial sectional view through a conduit mounted in the housing of Figure 10 between two walls of a container;

Figure 12 is an axial sectional view taken through a conduit mounted in the housing assembly of Figure 10, showing the manner in which the conduit passes through three walls of the container which are spaced apart and insulated from one another;

Figure 13 is a fragmentary sectional view taken along the line 13—13 of Figure 14, showing the

method of connecting a support between the inner walls of the container:

Figure 14 shows another modified form of my container illustrated in connection with a schematic layout of associated refrigerating, heating and evacuating apparatus;

Figure 15 is a vertical section taken through the rear wall of the container of Figure 7;

Figures 16 and 17 are elevational views of the end of the refrigeration coil housing of Figure 15, showing the split housing cover in closed and open positions, respectively;

Figure 18 is an enlarged fragmentary sectional view taken along the line 18-18 in Figure 15, showing the vacuum line and the manner in which it is carried through the chamber walls;

Figure 19 is an enlarged fragmentary view, in elevation, of the hinged door of Figure 14, showing the hinge mounting and the flexible conduit joining the interior of the hollow door to the evacuated wall of the container body;

Figure 20 is a fragmentary sectional view through the door of the container of Figure 7, taken along the axis of a locking rod and showing the arrangement of the locking wedge thereof;

Figure 21 is an elevational view, partially broken away, of the floating hinge assembly of Figure 19 with the hinge plate removed;

Figure 22 is a sectional view of the floating hinge taken along the line 22-22 of Figure 21;

Figure 23 is a sectional view taken along the line 23-23 of Figure 19, showing the arrangement of the flexible vacuum conduit between the door and the container;

Figure 24 is a side elevational view of my quick-detachable coupling assembly;

Figure 25 is a side elevational view of a modified form of the collar of my coupling assembly;

Figure 26 is a longitudinal sectional view taken through the assembly of Figure 24;

Figure 27 is a transverse sectional view taken along the line 27-27 of Figure 24;

Figure 28 is a transverse sectional view taken through a wall of my container constructed of collapsible panels, particularly showing the interlocking edge construction of pairs of both insulating and hollow panels;

Figure 29 is a sectional view taken along the line 29-29 in Figure 28 through the locking edges of the hollow panels;

Figure 30 is a perspective view of an edge of one of the hollow interlocking panels of Figure 29; and

Figure 31 is a partially sectioned enlarged detail of the liquid injector of Figure 14.

Figure 32 is a fragmental vertical sectional view taken thru the storage chamber of Figure 1, showing an additional pair of lines, 80a and 82a, for circulating heated and cooled air thru the innermost container 44.

Figure 33 is a partial vertical sectional view taken thru the container of Figure 14 showing the hot and cool air conduits provided with valve means for directing the respective air flow thru the storage space, the surrounding insulating chamber, or both.

Figure 34 is an enlarged sectional view taken thru the valve means of Figure 33.

It has been found that many articles of food may be better preserved during shipping and storage by use of a vacuum, either alone or in association with temperature control of the perishable article. By this means the necessity, for example, of freezing foodstuffs for future dis-

tribution may be obviated and a more palatable product obtained as well, since vacuum preservation does not change the character of organic tissues, destroy vitamins or flavors, or remove minerals. However, use of my containers to obtain below freezing temperatures is also contemplated.

Further, a vacuum has a high insulating value so that its employment jointly with heating or cooling means permits the maintenance of a more uniform temperature within a container, which is valuable whether or not the perishable items are stored in the evacuated section or not. Since the optimum environment for preservation of foods and beverages of course differs widely from one article to another, the desired treatment afforded different items necessarily differs and consequently I have provided containers with diverse arrangements of heated, refrigerated, and evacuated storage spaces therein.

Thus, for example, potatoes which are being shipped through freezing territory would be carried in a heated chamber, while fish and meat could be maintained at below freezing temperatures. Again, a rarified or evacuated atmosphere maintained at above freezing temperature is particularly advantageous for the shipping of ripe, freshly picked fruits and berries.

As shown in Figure 1, there is provided a generally rectangular shipping and storage container 40, within which are nested an intermediate container 42 and a central food receptacle 44, each of the three containers having a door or entrance 43, 48 and 50 at the same end so that entrance to the innermost receptacle is gained through the successive doors.

The inner containers are spaced apart along their sides, top and bottom by a series of laterally spaced, non-metallic or insulating, longitudinal rails, 52 and 54, located between the respective compartments, each rail containing a series of lateral apertures 56 to allow passage of air therethrough, the individual rails having their top and bottom edges disposed in corresponding channels 57 formed in pairs of oppositely aligned supports 58 which are mounted along the adjacent container walls or may be formed integral therewith. The supports serve both to restrain the rails against lateral movement and to facilitate insertion of the successive inner containers within the outer ones. A correspondingly positioned series of skids 60 are additionally provided on the bottom of the outer container for ease in moving the same about a floor or the like.

Evacuation of air from food container 44 is effected by a vacuum line 62, connected to an external vacuum pump (not shown) and controlled by an automatic pressure or vacuum switch in communication with the chamber by conduit 64. These lines, together with a water injector 66 and thermostat 68 enter the storage chamber through an insulating block 69 mounted along the back wall thereof. The inner ends of the members 62, 64, 66, and 68 are protected against contact with articles stored within the chamber by a perforated cover plate 70. The vacuum line 62 may extend horizontally along the end and side walls of the chamber as shown in Figure 6 to serve also as a guard or bumper for the walls, being provided with successive openings 63 to permit evacuation of air, such openings being spaced so that if one or more becomes clogged by the pressure of an article against it, the others will still permit the line to function.

Intermediate container 42 is also penetrated

with a vacuum line 72 and vacuum gauge 74 as well as a pair of conduits 76 and 78 for circulating hot or cold air through the chamber in response to the thermostatic control 68. A similar pair of air conduits 80 and 82 (which may also be responsive to thermostat 68) are provided for the outermost chamber, being disposed to penetrate a transverse insulating wall 84 disposed between containers 40 and 42 so as to separate the main air space 86 of the outer chamber from a rear chamber portion 88 thereof, within which rear portion the various conduits may be coupled from time to time with externally extending lines as described hereafter. Access to control chamber 88 is by way of an inverted L-shaped closure 90, hinged to the outer container 40 by recessed hinges 92 and provided with a suitable recessed catch to engage the top of the container at 94. A pair of similar catches 95 are likewise mounted on the front closure 46. In addition to the insulating effect obtained by the air space 96 between the two inner, spaced containers, and that of outer air spaces 86 and 88, further insulation against heat transfer is obtained through the use of insulating material 98 such as asbestos, pumice, fiber glass, sawdust, cork, etc., which fills the hollow walls of the outer shell 40.

For use in moving the container, a handle 100 (Figures 4-5) is provided at either end thereof, sunk within a recess 102 so as to lie beneath the outer surface of the container wall, said handle being provided with an outwardly extending, engaging lug 104 on either side thereof, so disposed as to abut against the face of the recess when the handle has been partly lifted, thereby avoiding crushing the fingers of the persons lifting it, as might otherwise happen if the handle were allowed to come up all the way.

Each of the inner compartments 42 and 44 is provided at its front end with an outwardly projecting flange 106 peripherally disposed about the aperture of the chamber, each flange having a groove 108 about its inner face adapted to be engaged by a plurality of locking wedges 110 mounted on the outer face of the door 48 or 50, so as to project beyond each edge thereof. Each of the locking wedges is disposed to move within a fixed guide collar 111, and is extended or retracted by means of an operating wheel 112 terminally mounted upon a threaded shaft 114 which in turn is journaled within a centrally located, generally rectangular frame 116 located on the outer face of the door, said shaft being threaded also through the tapped aperture of a square-ended actuating block 118, which is contained within the frame. The block or coupling 118 is restrained against rotary movement by four bell cranks, each having a short arm 120 which extends into a corresponding recess formed in the adjacent side of the block. Each of the bell cranks is pivotally supported at 126 on a bracket 128 formed on the inner surface of the housing 116 and has a long arm 122 extending generally parallel to the axis of the screw 114. The arms 122 are connected at their outer ends to radially extending, slidably supported locking arms 109 having wedge blocks 110 at their outer ends which engage the peripheral groove 108 in the flange 106 to draw the door tightly against the doorway. By this construction, rotation of the operating wheel 112, causes the block 118 to travel up or down along the shaft 114 as the case may be, causing each lever arm 122 to slide its corresponding locking wedge 110 in or out of the peripheral groove 108. In the alternative, the

locking arms may be positioned on the inner face of a door as in Figure 20, each wedge 110a engaging a correspondingly aligned stop or flange 129. Compressible (e. g. rubber) gaskets 32 are arranged about the door edges.

The several conduits which pass through the walls are enclosed therein by insulating housing 69. Although the conduits are depicted in Figure 1 as vertically spaced within the housing, the latter may conveniently be horizontally disposed as shown in Figure 10. As seen particularly in Figure 11, such a block is formed of a main body of non-metallic or insulating material 152 (for example, molded plastic) carrying a transverse conduit section 154 to which a pipe or similar attachment may be screw-threadedly attached. The chamber walls (42 and 44) are anchored to the block 152 by screws 156 which also engage a (cork or rubber) gasket 155 and a metallic reinforcing ring 159 peripherally mounted on the block and desirably welded to the adjacent container wall. When a conduit is carried through more than two walls the insulating block is desirably formed in several pieces for easy assembly, as shown in Figure 12, and an outer cover 157 may be molded integral therewith and provided with suitable openings 158 through which screws secure the outer wall to the housing.

In order to quickly connect and disconnect the several conduits entering the chamber, to the corresponding external vacuum or air lines, there is provided a novel coupling assembly, Figures 24-27, consisting essentially of a blunt-ended, inwardly sloping conduit terminus section 220 adapted to have its end wedged against a complementary obtuse, annular face 222 of a hose or pipe-end 224 by action of an independently rotatable collar 226 possessing an inwardly projecting flange 227 which is adapted to be brought into registration with the back of the outwardly extending annular face 222, said collar being designed to encircle jointly the ends of the conduit terminus 220 and pipe-end 224 and draw the two together by reason of engagement of a pair of inwardly slanted bayonet slots 228 (formed on either side of the collar), with a pair of radially projecting studs 230 mounted on opposite sides of the conduit terminus. In order to lock the opposite pipe and conduit members in this tightly engaged position, there is provided on the conduit terminus 220 an outwardly extending annular flange 231 having a series of closely placed, radially aligned notches 232 adapted to be engaged by a latch 234 swingingly mounted on a radially extending handle 236 of the collar. In a modified form of collar shown in Figure 25, instead of a handle, there is provided a generally annular neck formed integral with the body 226 and having an outer polygonal face 240 adapted to be engaged by a suitable wrench in order to effect rotation of the collar.

A modified form of my storage container is illustrated in Figures 7 and 15-18, this embodiment providing a vacuum storage container 242 disposed within a surrounding storage chamber 244, the temperature of the air in the latter being regulated by a refrigerating or cooling unit 246 and a heating unit 248, each of which latter are bolted onto the back of the container and situated in a generally cylindrical external housing, 249 and 250 respectively, similarly attached to the back of the container. This particular location of the heating and cooling units is not specified by way of limitation however, since these

units may be located elsewhere within the container as desired.

A split cover plate is provided for the outer ends of the cylindrical housings 249 and 250, the upper plate 190 (Figures 16 and 17) having a pair of pipe-receiving openings 188 formed along its inner edges as well as a pair of laterally spaced slots 192 and correspondingly shaped pair of ears 194 adapted to be received therein and held in such alignment by a latch 196 and pin 197.

Vacuum line 154a is adapted to evacuate either the vacuum chamber 242 or the insulating space 197 which surrounds both the vacuum storage chamber 242 and the heated and cooled storage chamber 244, the line serving further to evacuate hollow door 252 through a flexible conduit as will be shortly described. The manner of carrying the vacuum line through the pair of container walls is shown in Figure 18, there being provided an externally threaded plug 254 formed of insulating material and adapted to receive the vacuum line through its center and to screw-threadedly engage a corresponding aperture in the outer container wall 256 so that upon insertion therein it will act to compact an annular plug 258 formed of compressible insulating material (for example rubber) surrounding the conduit and having its opposite face in abutment against inner insulating wall 260.

Inner walls 260 and 262 are held in spaced relation by means of lateral supports 164 which are secured to each adjacent wall by a bolt 168 (Figure 13) said supports being at the same time held from direct contact with either the wall or the bolts by means of a flat insulating washer 172 disposed on one side of the support, and on the opposite side by an insulating sleeve 174 having a terminal, outwardly flanged flat portion 175 adapted to be sandwiched between the two members. Thus, it will be seen that the container walls, supports and conduits may be formed of metal to insure strength but are restrained from heat conducting, metal-to-metal contact by such structures as the insulating rails 52 and 54, the conduit housing block 69, the end insulating walls 84, the lateral support mountings 172 and 175, and the insulating structures of Figure 18.

Another modification of my container is illustrated in Figures 14, 19 and 21-23, the container 40a being provided with an outwardly sloping doorway and a correspondingly wedge-shaped hollow door 46a which seats therein. One hinge plate 130 is attached to the sloping edge of the door in the conventional manner while its companion hinge plate 132 is secured by suitable screws to a horizontally slidable block 134, normally urged to one side by a pair of coil springs 136 which are held in alignment therewith by a corresponding pair of centering pins 138 extending from the side of said block so as to form a partial core for each coil spring. The sliding block and springs are in turn retained within a recess in the sloping doorway by means of a cover plate 140 having a pair of horizontal slots 142 to permit passage of screws 144 which connect the hinge plate 132 to the sliding blocks. By this arrangement there is obtained a highly effective automatic centering of the inwardly slanted edges of the door within its sloping doorway as extension of the locking wedges 110 thus serves to force it into airtight alignment.

A further feature of the present construction is the provision of a hollow chamber within the door panel 46a which may be evacuated together

with a vacuum chamber of the container, and to effectuate this, a flexible conduit 146 is provided to connect the door chamber with the body chamber, said conduit being adapted to lie in its collapsed position (that is, when the door is closed) within a complementary pair of corresponding recesses 148 and 150 formed respectively along the hinge edge of the door and the adjacent face of the container. A similar attachment is also provided between the hollow door 252 and the vacuum chamber 197 of the container of Figures 7 and 15. A vacuum release valve 151 is also present on the several vacuum doors in order to permit entry of air to the inner chambers so as to facilitate opening the doors thereof.

A somewhat schematic arrangement of elements adapted to service my food containers is also shown in Figure 14, there being provided a vacuum pump 198 responsive to automatic pressure switch 199, a heating coil 200 and a cooling unit composed of compressor 202 and condenser tubes 204 and evaporator tubes 205 for vaporization of liquified ammonia or other refrigerant. Air which has been warmed or cooled is circulated through conduits 82 and 80 by electrically driven fans 206 and 208 respectively, the heating and cooling systems both being operated by thermostatic control 201. Each air conduit 80 and 82 contains a shut-off or damper 81 and 83 respectively, by means of which the air coming out of the chamber is by-passed around the heating or cooling unit as the case may be, thus preventing, for example, exposure of air-cooling tube 205 to warm air moving out through conduit 80. An atomizer member 214 (Figure 31) is additionally provided for injecting water or other liquid into the food storage chamber from time to time in order to maintain the moisture content thereof or to supply a preservative spray as desired.

Since the heating and refrigerating units as well as the atomizer, pressure switch and thermostatic control are of conventional design they will not be described in detail.

By still another modification, my vacuum container may be constructed from demountable interlocking panels (Figures 28-30). A lining of connected hollow panels 175 is sandwiched between outer panels 176 formed of insulating material, and the storage chamber thus formed and/or the hollow sections of the connected panels 175 may be evacuated or, in the alternative supplied with cooled or heated air as in the earlier described forms. The hollow panels are constructed with a longitudinal lip 178 extending along an edge and arranged to overlie a complementary lip 179 of the adjoining panel, the lips being provided respectively with male 177 and female 180 guide members, designed to snugly engage each other and permit circulation or evacuation of air through passageways 183 which thus join the interiors of adjacent panels. The lips 178 and 179 are held in frictional engagement by screws inserted jointly through transverse, aligned channels 181 and 182 formed by cylindrical walls in the respective lips, the former channel being internally threaded, it being observed that both channels are open at either end but are at no place in communication with the hollow or vacuum sections of their panels. Analogous lip sections of the insulating panels 176 are strengthened by insertion therein of U-shaped sleeves or braces 184 and are fastened together by suitable screws 186 therethrough.

While I have shown and described in some detail some presently preferred embodiments of my

vacuum container, it is to be understood that various modifications may be made in the construction and operation thereof within the scope of the subsequently claimed invention.

The invention claimed is:

1. A container for preserving perishable goods including: a plurality of nested chambers each with its own closure, said chambers being spaced apart to form closed insulating space therebetween, the innermost of said chambers being adapted for use as a storage chamber and at least one of said chambers having an inwardly tapered wall forming an entrance thereto; a closure for said chamber having a complementary tapered wall adapted to frictionally engage the tapered wall of said chamber; a hinge assembly having one hinge plate secured to each of said tapered walls and adapted to lie in juxtaposition when the door is closed, one of said plates being adapted for limited movement along said tapered wall so as to permit self alignment of the closure within said chamber entrance; locking means on said closure adapted to draw the same tightly against said closure entrance; means for selectively evacuating said storage chamber and said insulating space; and means adapted to circulate cooled or heated air selectively through said storage chamber and said insulating space.

2. A container for preserving perishable goods including: a plurality of nested chambers spaced apart to form a closed insulating space therebetween, at least one of said chambers being adapted for use as a storage chamber; means for evacuating at least one of said chambers; and other means for circulating temperature-controlled air thru said other chamber said last means being disposed, at least in part, within a tubular housing detachably connected to the outermost chamber, which housing is provided with a split cover plate formed with pipe receiving openings along its intersection and having locking means therefor, and corresponding projecting lugs and aligning slots formed along said intersection.

3. A container for preserving perishable goods including: a plurality of nested chambers each with its own closure and spaced apart to form closed insulating space between chambers, the innermost of said chambers being adapted for use as a storage chamber, longitudinal rails disposed between said nested chambers so as to space them apart, the rails being laterally separated from each other, provided with transverse apertures to allow passage of air therebetween within the closed insulating space, and being retained in

complementary channels formed along opposing faces of the walls of adjacent chambers, and coupling means carried by each chamber for connection to external means adapted to evacuate and to circulate cooled or heated air selectively through said storage chamber and said insulating space.

- 5 4. A container for preserving perishable goods including: a plurality of nested chambers each with its own closure and spaced apart to form closed insulating space between chambers, the innermost of said chambers being adapted for use as a storage chamber, coupling means carried by each chamber for connection to external means adapted to evacuate and to circulate cooled or heated air selectively through said storage chamber and said insulating space, the outermost chamber of which is provided with longitudinally directed skid rails on its bottom and has a second 10 closure adapted to give access to said coupling means carried by inner nested chambers, and the innermost chamber is provided with a vacuum conduit extending around its inner sides so as to 15 serve as well as a bumper guard for goods placed 20 therein.
